ELECTRIC CONNECTOR FOR CORONA
DISCHARGE DEVICES

Edgar B. Nichols, Moorestown, N. J.

Application April 13, 1944, Serial No. 530,813

3 Claims. (Cl. 173—324)

1

This invention relates to electrical connectors, and it has particular relation to connectors suitable for use at high voltages, the present application being a substitution in part for my prior abandoned application, Ser. No. 449,219, filed July 1, 1942.

There are various types of electrical apparatus which are operated at high voltages. At these voltages, it is not unusual for corona discharges to take place which very greatly shorten the life of connectors employed to connect such apparatus to other apparatus. This is due in many instances, among other things, to rough or sharp surfaces on the connectors along which the electron streams are highly concentrated, or to constructions which do not permit sufficiently tight or firm connection with terminal elements of the apparatus, and to other similar causes.

The principal object of my present invention is to provide an improved terminal connector for electrical apparatus which is suitable for use at high voltages.

Another object of my invention is to provide an improved terminal connector which is free from rough or sharp edges, points and other similar surfaces.

Another object of my invention is to provide an improved electrical terminal connector which will grip the terminal elements very firmly and tightly.

Another object of my invention is to provide an improved electrical terminal connector which is self contained and therefore requires no external supporting means for the purpose of mounting.

Another object of my invention is to provide an improved terminal connector which readily lends itself to use in places to which access is difficult.

Another object of my invention is to provide an improved terminal connector which will readily dissipate the heat developed therein at high operating voltages.

Another object of my invention is to provide an improved terminal connector which is comprised of a minimum number of parts, is simple in construction, and highly efficient in use.

I accomplish the aforementioned and other ancillary objects by providing a spherical or ball-shaped clamping member which has a diametric bore terminating in a conical seat at one end. Into this bore is placed a tubular collet formed with a conical head at one end which cooperates with the conical seat in the clamping member. When the bore of the collet is slipped over a ter-

2

rninal element and the head of the collet is drawn down firmly against the conical seat, its jaws tightly grip the terminal element. Due to the smooth surface of the spherical clamping member, no sharp edges, points or other similar surfaces are present on which electron streams can concentrate. Therefore, my improved connector is free from corona discharges and from the inherent disadvantages resulting therefrom.

10 The invention is susceptible of a variety of forms. Its advantages, and other inherent objects thereof, will be readily understood, however, from the following description of several different forms when read in connection with the accompanying drawing in which

Figure 1 is a view partly in elevation and partly in section showing one form of my invention,
Figure 2 is a perspective view of the collet,

Figure 3 is a view partly in elevation and partly in section of a clamping member formed according to another embodiment of my invention,

Figure 4 is an enlarged, fragmentary perspective view of a portion of the clamping member shown in Figure 3,

25 Figure 5 is a view similar to Figure 1 showing still another and preferred form of my invention,
Figure 6 is a side elevation of the collet used in the form of the invention shown in Figure 5, and

30 Figure 7 is an elevation of a slightly modified form of the invention shown in Figure 5.

Referring to the drawing in greater detail, Figure 1 shows a terminal connector having a clamping member 10 which has a smooth, continuous surface in all directions so as to provide no sharp, pointed or rough edges. The member 10 may be of any suitable shape, such as a sphere, an ellipsoid, or any other similar surface of revolution, the shape shown being that of a sphere for the sake of illustration. The member 10 is formed with a diametric bore 11 terminating at one end in an outwardly diverging seat 12, such as a cone or the like.

45 Within the bore 11 is fitted a collet 13 having a central bore 14 and provided with threads 15 at one end. The other end of the collet terminates in a head 16 shaped exteriorly to conform to the shape of the seat 12, being conical in this instance. The head 16 is split radially outwardly from the bore 14 by a plurality of circumferentially distributed, longitudinally extending slits 17. The slits 17 divide the head 16 into a number of jaws which, when forced together, firmly grip 50 a terminal element 18, such as a prong of a radio

tube, for example, previously received within the bore of the collet.

The collet 13 is appreciably longer than the diameter of the clamping member 10. Thus, when the collet is inserted into the bore 11, its threaded end extends beyond the member 10, as clearly seen in Figure 1. A knurled nut 19 is threaded on the threads 15 and bears against the member 10. As the nut 19 is advanced on the collet 13, it is obvious that it will draw the head 16 of the collet tightly into seating engagement with the seat 12. The seat 12, in turn, forces together the jaws of the collet head 16 to cause these jaws to firmly grip the terminal element 18.

When applied to apparatus which operates at high voltages, as in the case of radio transmitter tubes, for example, considerable heat may be developed in the connector. To provide a construction in which the heat will be rapidly dissipated, the clamping member 10 may be formed with a plurality of slots, as shown in Figure 3. One set of slots 20 may extend circumferentially around the member 10 in parallel relation and for a substantial depth toward the bore 11. Another set of slots 21 may extend in planes at right angles to the slots 20 and may be of the same or different depth, as found suitable. While the slots 21 may also be parallel to each other, if desired, they are shown, by way of illustration, as lying in planes which intersect each other at the diameter of the member 10 which constitutes the axis of the bore 11. In any case, a plurality of sector-like, radially outwardly extending, spaced fins 22 are thus formed which have a total area sufficient to rapidly dissipate the heat developed in the connector at high operating voltages. To eliminate sharp edges on the fins 22 formed by the intersecting slots 20 and 21, which normally invite corona discharges at high voltages, the edges 23 thereof are preferably rounded off. In this way, a condition normally conducive to corona discharges is eliminated.

In certain instances, the terminal element 18 may be in such a location that it is difficult to reach it with the fingers. For such instances, the clamping member 10 may be formed with a radial or other suitably arranged bore 24 constituting a socket for the reception of a removable handle or other suitable tool 25. By means of the handle 25, application of the connector to terminal elements in places normally hard to reach is made easy.

The forms of my invention thus far described are usually satisfactory at moderately high voltages. At very high voltages, however, it may be found that the knurled nut 19 or the fins 22 occasionally tend to invite a corona discharge. To avoid this, I preferably form the connector in the manner illustrated in Figures 5 and 7. In this form of my invention, the connector is made in two complementary parts which, together, form a sphere or other suitable surface of revolution, the form shown in Figure 5 comprising two, cooperating, hemispherical parts 26 and 27 formed with aligned bores 28 and 29. The bore 28 is formed with the seat 12 and the lower end of the bore 29 is threaded for cooperation with the threads 15 of the collet. After inserting the collet 13 into the bore 28, the part 27 of the connector is threaded onto the threads 15 and tightened against the part 26. This draws the collet head 16 into firm seating engagement with the seat 12 to cause the jaws of the collet head to firmly grip the terminal element. A flat 30 on the

shank of the collet cooperates with a similar flat in connector part 26 to prevent the collet from turning as the connector part 27 is tightened against the part 26.

The modification of Figure 7 is similar to that of Figure 5 except that the connector part 26a is formed of a spherical segment which is larger than a hemisphere and the cooperating part 27a is formed of a spherical segment which is smaller than a hemisphere. In either case, the parts 26 and 27, or 26a and 27a together form a sphere or ball having a continuous smooth surface in all directions and devoid of portions which tend to invite a corona discharge even at extremely high operating voltages.

From the preceding description, it is apparent that I have provided an improved terminal connector having many inherent advantages. Not only does the smooth, continuous surface of the 20 spherical or other similar clamping member avoid the likelihood of a corona discharge with the attendant dangers, but also, the terminal element is firmly gripped by the jaws of the collet head 16 to provide a tight connection. A flexible or 25 other suitable lead 31 may be inserted through the end of the collet 13 opposite the head 16 and permanently secured in place within the bore thereof, as by solder, to provide a connecting lead to other apparatus or devices. It will also be 30 apparent that my improved connector needs no supporting panels, terminal plates, or other devices to support it and that it can be applied directly to many types of terminal elements.

Having described my invention in considerable detail, I claim:

1. In a self contained electrical connector, a clamping member having a smooth, continuous surface in all directions and provided with a bore terminating at one end in an outwardly diverging 40 seat, a collet fitted in said bore, said collet also having a bore therethrough and including a head shaped exteriorly similarly to said seat, said head being split radially outwardly from said last named bore and being adapted to receive a terminal element, and means including a portion of said clamping member for drawing said collet head tightly against said seat whereby said seat is adapted to force said head into firm gripping engagement with said terminal element, wherein 45 said clamping member comprises a pair of complementary parts which together constitute a sphere, said parts having aligned bores and said seat terminating the bore of one of said parts, characterized further in that said collet extends clear through the bore in said first named part and into the bore of the other of said parts, and characterized still further in that said other part is threaded on said collet for coaction with said first named part to draw said collet 50 head tightly against said seat.

2. In a self contained electrical connector, a clamping member comprising a pair of complementary parts which together constitute a geometric figure having a smooth, continuous surface in all directions, said parts having aligned bores therethrough, the bore of one of said parts terminating at its outer end in an outwardly diverging seat, and a collet fitted into said bores, said collet extending clear through the bore in said one part and into the bore in the other of said parts, said collet also having a bore therethrough and including a head shaped exteriorly similarly to said seat, said head being split radially outwardly from said last named bore and being adapted to receive a terminal element, said

other clamping member part being threadedly received on said collet for coaction with said one part to draw said collet head tightly against said seat whereby said seat is adapted to force said head into firm gripping engagement with said terminal element.

3. An electrical connector according to claim 2 wherein said clamping member parts together constitute a sphere.
